UNITED STATES PATENT OFFICE.

JOHN H. SHAW, OF NEW HAVEN, CONNECTICUT, ASSIGNOR TO SARGENT & COMPANY, OF NEW HAVEN, CONNECTICUT, A CORPORATION OF CONNECTICUT.

LOCK.

1,089,977.

Specification of Letters Patent.

Patented Mar. 10, 1914.

Application filed September 23, 1911. Serial No. 650,901.

To all whom it may concern:

Be it known that I, JOHN H. SHAW, a citizen of the United States, residing in the city and county of New Haven, State of Connecticut, have invented new and useful Improvements in Locks, of which the following is a full, clear, and exact description, when taken in connection with the accompanying drawings.

10 My invention relates to locks, and its object is to provide an improved and simplified construction of night latch mechanism.

My invention is illustrated in the accompanying drawings, in which,

15 Figure 1 is a side view in elevation of a lock with the cap plate removed; Fig. 2, a similar view with the dogging slide of the night latch mechanism in dogging position, showing the door closed, and the releasing 20 thumb stop slide controlling the dogging slide automatically dogged; Fig. 3, a view similar to Fig. 1, with the latch bolt inside hub yoke, dogging member and automatic bolt removed; Fig. 4, a view similar to Fig. 3, 25 with both the thumb stop slides protracted; Fig. 5, a detail plan view of the connecting lever between the two slides; Fig. 6, a detail edge view of the upper thumb stop slide; Fig. 7, a similar view of the automatic bolt, 30 and Fig. 8, a similar view of the dogging slide.

In all figures, similar letters of reference represent like parts.

Referring to the drawings, 1 is a latch bolt having at the inner end of the shank a head 2, which is adapted to be engaged by a yoke 3. The yoke 3 is actuated by the wings of an outside hub 4 and an inside hub 5. The outside hub 4 has a notch 6 which 40 is adapted to receive the end of a night latch member or dogging slide 7, the front end of which is provided with a thumb stop 8 projectable through the face plate 9 of the lock. A spring 10 carried by the slide 7 is adapt- 45 ed to engage the post 11 rising from the casting for the purpose of retaining the slide in protracted or retracted position. On its under side the slide is provided with a stud 12. This stud engages an open slot formed 50 by the forked arms 13 of the lower end of a walking beam or connecting lever 14 which is pivoted centrally at 15 to the casting. The upper end of the lever is pro- 55 vided with an arm 16 projecting vertically

upward. This arm projects behind a stud 55 17 extending from a thumb stop slide 18, whereby whenever the thumb stop slide is pushed inwardly the connecting lever will be pushed back by the same so as to protract the dogging member 7 and thus release the 60 outside hub. Moreover the dogging slide 7 may be protracted from dogging position to release the hub even when the upper actuating slide is in protracted position, which latter movement is effected by reason of the 65 fact that the stud of the upper slide has a bearing against the connecting lever only on the rear side of the stud and has a forward movement independent of said connecting lever.

70

Projecting through the face plate is the head 19 of an automatic false bolt 20, which has a depending vertical arm 21 provided with a lug 22. The lug 22 is adapted to engage the lower edge of a lever 23 which 75 constitutes a dogging member and is adapted to dog the upper slide 18 and the head of the latch bolt. A shoulder 24 on said lower edge of the dogging member engages with the lug 22 of the automatic false bolt 80 20 so that when said bolt is in its normal protracted position when the door is open, the dogging member will be held out of dogging position relative to the slide and latch bolt. When the door is closed the bolt 85 20 will be moved and held inwardly by contact with the striker plate and a spring 25 connected to the rear arm of the lever 23 will tilt said lever on its pivot so as to carry the front end thereof down into dog- 90 ging position behind the heads of the thumb stop slide and the latch bolt. To this end, the front end of the dogging member is provided with two dogging arms 26 and 27 spaced apart vertically and adapted to 95 straddle the head of the slide 18 when the door is in open position. When the door is closed, however, and the bolt is actuated as before described, the upper arm 26 drops behind the head of the slide 18, and the 100 lower arm 27 drops behind a shoulder on the head of the latch bolt. Owing to the one way operative connection of the releasing slide with the lever, the outer manual retracting means for the bolt is prevented 105 from operation without the necessity of dogging the night latch slide 7.

Having now described my invention, what

I claim and desire to secure by Letters Patent, is:—

1. In a lock, the combination with a hub, of a dogging member therefor, a releasing member for said dogging member, and a walking beam between said members having a one-way connection with one of them; substantially as described.
2. In a lock, the combination with a hub, of a dogging slide therefor, a releasing slide for said dogging slide, and a walking beam connecting said slides and having a one-way connection with one of them; substantially as described.
3. In a lock, the combination with a hub, of a dogging slide therefor, a releasing slide

for said dogging slide, and a walking beam connecting said slides and having a one-way connection with said releasing slide; substantially as described.

4. In a lock, the combination with a hub, of a dogging slide therefor, a releasing slide having a stud, and a connecting lever between said slides having a single arm projecting across the stud of said releasing slide; substantially as described.

In witness whereof, I have hereunto set my hand on the 20th day of September, 1911.

JOHN H. SHAW.
